BOAT CONSTRUCTION

Haymo Victor Pfister, Martinsville, N. J.

Application June 8, 1939, Serial No. 278,000

3 Claims. (Cl. 9—6)

The present invention relates to a boat construction and particularly relates to a boat construction which is adapted for children's use as well as adults' use.

5 It is among the objects of the present invention to provide a simple, compact boat unit, which boat unit may be readily made in varying sizes and which boat unit may be made so as to permit several boats to be nested together and sold or transported in such nest as a single unit.

10 Another object is to provide an inexpensive yet durable boat construction which may be made in very small sizes for use as a toy and in very large sizes for use as a conveyance and which at 15 the same time will be of such light weight it may be readily transported or handled.

Still further objects and advantages will appear from the more detailed description set forth below, it being understood, however, that this 20 more detailed description is given by way of illustration since various changes therein may be made by those skilled in the art without departing from the scope and spirit of the invention.

25 In accomplishing the above objects, it has been found most satisfactory to use a boat constructed with relatively light wood sides and ends and at the same time to provide a fibrous or multilayer bottom construction which may be attached to 30 said sides.

In one form of the invention it has been found most desirable to cause the boat to have a substantially rectangular outline with the side walls forming the long walls of the rectangle and the 35 end walls forming the short sides of the rectangle. The bottom, which is attached to the side and end walls, is preferably turned upwardly toward the end walls, such end walls being of substantially less depth than the middle portions of the 40 side walls.

In the preferred construction, to enable more ready nesting of the boats, the side walls are inclined inwardly and upwardly so as to permit the 45 positioning of an anti-splash rail at the tops of said walls. The outer edge of this anti-splash rail should preferably not project beyond the outer edge of the bottom of the boat so that the boats may be readily nested together in different 50 sizes in units of two, three, four or even five or more.

Referring to the drawing which illustrates several of the various possible embodiments of the present invention, but to which the present invention is by no means restricted since the draw-

ing is merely by way of illustration and not by way of limitation;

Figure 1 is a top view of a nest of three of the boats according to one form of the present invention;

Figure 2 is a side view upon the line 2—2 of Figure 1;

Figure 3 is a transverse sectional view upon the line 3—3 of Figure 1;

Figure 4 is an end view upon the line 4—4 of Figure 1; and

Figure 5 is a fragmentary transverse sectional view upon the line 5—5 of Figure 1 upon enlarged scale as compared to Figure 1.

Referring to Figure 1, the nest as shown has 15 three boats A, B and C, each of which is of identical construction although of different dimensions so as to nest together.

Each boat, as shown, is provided with side walls 10 and end walls 11 of a varnished or lacquered light wood, the side walls 10 overlapping the ends of the end walls 11 at 12, as shown in Figure 2, and being held in position by the screws 13, then form a watertight joint.

The end walls 11 are shorter than the middle 25 portion of the side walls 10 and the ends of the side walls are cut upwardly, as indicated at 14, toward their junction 12 with the end walls 11.

The base or bottom 15 is preferably of a flexible impregnated sheet material which may be 30 impregnated with resins or other plastics and which is held in position by the screws 16 to the end walls 11 and by the screws 17 to the side walls 10.

The bottom may be composed of sheet fibrous 35 material impregnated with a resin or lacquer which sheet is shaped in forming to conform to the bottom edges of the side walls 10 and the end walls 12.

It will be noted, as shown best in Figure 5, that 40 the side walls 10 are of decreasing thickness upwardly and their outer surfaces inclined inwardly, as indicated best at 18.

This inclination and decrease in thickness will compensate for the thickness of the side or splash 45 rails 19, the outer edges 20 of which are directly above the outer edges 21 of the bottom 15 (see particularly Figure 4).

In this manner, it is possible to nest the boats more compactly together, as indicated in Figures 50 1, 3 and 5, and the side splash rail also will cooperate with the flat shaped bottom to prevent undue splash in the boat when the boat is used.

If desired, instead of decreasing the thickness 55 of the side walls 10, the side walls may be made

of uniform thickness and the side edges of the end walls may be caused to incline inwardly from the bottom to the top of the boat.

The boat which is constructed in the manner shown in Figure 4, when made of light weight materials, preferably light weight woods, surfaced with suitable varnishes or lacquers, is low in weight, easy to handle, economical to construct and maintain and by reason of the nesting possibilities, a number of boats ranging from two to five or more in number may be placed inside of each other and take up only the room occupied by the largest boat.

Although the square or rectangular shape is preferred, the boats may also be constructed with a pointed or curved nose or stern and they may be constructed of other materials than wood, for example, of metals and compositions.

The anti-splash rails 19 will prevent small waves from splashing over into the boats and the curvature, as indicated at 22 in Figures 4 and 5, is particularly satisfactory for this purpose.

Although synthetic fibrous materials are preferred for the bottom 15, it is also possible to use metals, various types of light weight cements or laminated constructions, ply wood and so forth.

The joints at 23 in Figure 1 and at 24 in Figure 2, may be readily sealed by materials such as tar, white lead, rubber, and so forth.

Where the boat is made of light weight metal materials, instead of the screws as shown, the entire construction may be welded, soldered or riveted together.

The anti-splash rail 19 is particularly desirable inasmuch as it not only prevents splashing, as above stated, but provides additional strength for the top of the boat and provides a convenient means for handling the same.

Although many types of woods may be utilized for the end walls 11 and the side walls 10, it has been found most satisfactory to employ cedar or red wood and to use as a sealing composition between the crevices, a white lead colored to match these woods and some fibrous binding material, such as cotton wicking or felt.

Boats built in this manner, measuring about 4 feet, 6 inches long, and 16 inches wide, weigh about 14 pounds and can conveniently carry children weighing between 50 and 75 pounds. Slightly larger boats measuring about four feet, nine inches long by eighteen inches wide can conveniently carry children between 75 and 100

pounds. Slightly larger boats will carry proportionately heavier people.

The sides of the boat may be normally approximately 8 to 10 inches high and about $\frac{3}{4}$ of an inch thick on the thick end and about $\frac{1}{4}$ of an inch thick on the thin end. The decrease of approximately $\frac{1}{2}$ of an inch between the thick end and the thin end allows the installation of an anti-splash rail of $\frac{1}{2}$ inch in thickness without decreasing from the size of the boat itself.

It is apparent that the specific illustrations shown above have been given by way of illustration and not by way of limitation and that the structures above described are subject to wide variation and modification without departing from the scope or intent of the invention, all of which variations and modifications are to be included within the scope of the present invention.

What is claimed is:

1. In a nest of boats, each boat comprising side and end walls of a light wood, and an impregnated fibrous sheet bottom attached to the bottom of said side and end walls, said side walls decreasing in depth toward the end walls, said side walls being inclined inwardly toward their upper edges and anti-splash rails being provided at the upper edges of said side walls, said anti-splash rails projecting sufficiently so that their outer edges will be substantially directly over the outer edge of the bottom of the boat.

2. A nest of boats comprising a plurality of shallow boats of the same contour but of slightly different dimensions so that they may nest together, the side walls of said boats being inclined inwardly toward their upper edges and anti-splash rails positioned along the upper edges of said side walls, said splash rails projecting sufficiently so that their outer edges will be directly over the outer edges of the bottom of the boat.

3. A boat construction comprising side and end walls of a light wood, and an impregnated fibrous sheet bottom attached to the bottom of said side and end walls, said side walls decreasing in depth toward the end walls, said side walls being inclined inwardly toward their upper edges and being provided at their upper edges with anti-splash rails, said anti-splash rails projecting sufficiently so that their outer edges will be substantially directly over the outer edge of the bottom of the boat.
